CLAIM

The ornamental design for a land clearing tool interface, as shown and described.

DESCRIPTION

FIG. 1 is a front perspective view of a land clearing tool interface showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a rear perspective view thereof;

FIG. 9 is a front perspective view of another embodiment of the land clearing tool interface showing our new design;

FIG. 10 is a front elevation view thereof;

FIG. 11 is a rear elevation view thereof;

FIG. 12 is a right side elevation view thereof;

FIG. 13 is a left side elevation view thereof;

FIG. 14 is a top plan view thereof;

FIG. 15 is a bottom plan view thereof; and,

FIG. 16 is a rear perspective view thereof.

The dashed broken lines in FIGS. 1-16 represent portions of the land clearing tool interface that form no part of the claimed design.

The line shading in FIGS. 1-16 represents contour and not surface ornamentation.
